INTERLOCKING MACHINE FOR RAILROADS

Winthrop K. Howe, Rochester, N. Y., assignor to
General Railway Signal Company, Rochester,
N. Y.

Application July 23, 1929, Serial No. 380,418

22 Claims. (Cl. 246—136)

This invention relates to interlocking systems for railroads, and more particularly pertains to interlocking machines used therein.

Among the objects of this invention is to provide a compact organization of interlocking control devices, which are grouped into what is commonly known as an interlocking machine, in such a manner, that all control devices are easily accessible for inspection, adjustment and repair. 10 Also, it is a further object of this invention to provide an interlocking machine having control levers movable in a reciprocating manner, and employing the so called latch locking principle, that is, that type of lever, in which the lever is 15 locked in extreme positions by a lever latch, which in turn is locked by the usual mechanical interlocking between levers. A further object of the invention is to provide a mechanical stick type push button circuit controller, which is used in 20 conjunction with certain signal control levers for operating a "call-on" signal associated with the signal governed by that particular control lever.

Other objects, purposes and characteristic features of the present invention will be in part obvious and in part pointed out as a description of the accompanying drawings progresses.

In describing the invention in detail, reference will be made to the accompanying drawings, in 30 which like reference characters in the several figures refer to the same objects, and in which:—

Fig. 1 is an end view of an interlocking machine as included within the present invention;

Fig. 2 is a fragmentary view of the interlocking machine shown in Fig. 1, showing the arrangement of levers, the indication lights and the push button controls;

Fig. 3 is a side elevation of the mechanical stick type push button circuit controller as included within the present invention;

Fig. 4 is a section of an interlocking control lever as included within the present invention, being taken on lines 4—4 of Fig. 5;

Fig. 5 is a top view of the interlocking lever shown in Fig. 4.

With reference to the drawings, Fig. 1 shows the various control devices, control levers and electromagnetic devices associated with one control lever of an interlocking machine. It is of course understood that a complete interlocking machine is composed of a plurality of similar control levers which have similar parts and control devices associated with each lever, but it is deemed unnecessary to show and describe more than those devices and functions associated with

one particular control lever. The interlocking machine of the present invention may be used in any well known interlocking system arrangement, one of which is fully described in my Patent No. 1,550,611, dated August 18, 1925.

With reference to Fig. 1, the interlocking machine of the present invention has been shown as having two vertical bed sections, and one horizontal bed section, that is, the various members which lie in a longitudinal direction in respect to the interlocking machine as a whole, and furnish a support for the various control devices, may be conveniently termed bed members. These bed sections of the interlocking machine are supported by three part frames, that are equally spaced throughout the length of the interlocking machine, which frame work is composed of front leg members 1, back leg members 3, and cross members 2. On each cross member 2, dowel pins 4 and 5 are furnished for aligning the cross members 2 with their respective leg members 1 and 3, which members are securely fastened in place by bolts 6 and nuts 7.

The left hand vertical bed is composed of bed members 8, 9, 10, and 11, which connect the leg member 1 (see Fig. 1) with the next similar leg member (not shown) placed at a certain predetermined number of levers through the length of the interlocking machine. These bed members 8, 9, 10, and 11 furnish supporting means for sections of the mechanical interlocking plates 13, 14 and 15, which plates serve as guides for the usual tappet bars, locking bars, and locking dogs.

A bed member 16, composed of equally spaced guiding slots for the control levers, such as lever L, is mounted upon the frame cross member 2 (see Fig. 1) and the next succeeding frame cross member (not shown). The indication latch mechanism 17 is mounted beneath the bed member 16, being supported at the left (see Fig. 1) by bed member 8 and supported at the right by a wedge member 20, which is secured in position by a bolt and nut 19. Such a manner of mounting for the latch mechanism 17, permits each unit to be detached separately when desirable. This latch mechanism 17 is constructed in a manner to prevent the control lever L with which it is associated, from being moved to extreme positions until the latch mechanism 17 has been acted upon by the energization of the indication magnet 18.

Mounted upon the upper side of the bed member 16 is the force drop lock 21, which has a solenoid capable, when energized, of raising a locking dog (not shown) which normally engages the lever L to lock it in certain predeter-

mined positions. This locking dog is forced into its locking positions by the movement of the lever L to any new position.

A mechanical stick type push button circuit controller 22 is mounted on the upper side of the bed member 16, in such a manner, that the control lever L which is associated with it, is directly beneath it, and the coacting operation of said circuit controller will be described herein- 10 after.

The horizontal bed section is further composed of bed members 23, 24, 25, 26, 27, 28, and 29, which also connect the frame cross member 2 with the next succeeding frame cross member 15 (not shown) and serve as supports for the various control devices. A suitable circuit controller 30, such for example as described in my Patent No. 1,506,179, dated August 26, 1924, is mounted upon the bed members 23 and 24, and is operated by the lever L in the usual reciprocating manner. The bed member 25 is formed of wood or other suitable insulating material, and serves as a supporting means for the indication selector 31. This indication selector 31 may be 25 any suitable type of selector, one type of which is shown in my above mentioned Patent No. 1,550,611. The bed members 26 and 27 are also composed of wood or other suitable insulating material and are mounted upon the frame cross 30 member 2 in conjunction with a bracket member 67 in such a manner that an L-shaped mounting is formed for the various polarized cross-protection relays 32, which may be of any suitable type, one of which is disclosed in the patent 35 to J. C. Lindner, No. 1,676,340, dated July 10, 1928. At the extreme right of the interlocking machine, the bed members 28 and 29 serve as supports for suitable fuse blocks 33 having the usual terminals and such other modifications as 40 go therewith.

The leg members 3 serve as supports for the right hand vertical bed section which is composed of bed members 34, 35, and 36, having angle iron shape, and to which certain circuit controllers of the various levers may be attached. The particular circuit controller shown in Fig. 1, is one of the reciprocating type having a terminal board 37 upon which are mounted suitable contacts 38, which at certain times are interconnected by metal rings 39 mounted upon the slide- 45 able rod 40 and insulated therefrom.

The rod 40 is slidably mounted by support members 41 in such a manner that it may be controlled in a vertical direction by movement 55 of a lever arm 42. This lever arm 42 is mounted at a pivot point 43 upon a suitable bed member 44 and is interconnected with the lever L by a pin 45 which slides in a slot in lever L to rock the lever 42 upon its pivot point 43. This 60 rocking movement of lever 42 is transformed into reciprocating motion of the rod 40 by the interconnection of rod 40 with lever 42 by a link 46. Also, the terminal boards 47 and 48 are mounted upon the inside of the frame leg members 1, which mounting is made possible by the characteristic manner in which the interlocking machine of the present invention is supported and arranged.

70. It will be noted that the frame leg members 1 and 3 are supported by I-beams 49 and 50 running lengthwise of the interlocking machine. These I-beams 49 and 50 are placed at the edge of a suitable pit or depression within the floor 75 of the interlocking tower, which provides ample

space for an electrician or maintainer to inspect and take readings of voltage and current values along the terminal boards 47 and 48, remove indication latch mechanisms, or do any other inspection or repair work which might be required 5 beneath such an interlocking machine.

It will be noted, that the machine is suitably covered with an inclosing framework, which in this case is composed of wooden panels 65 and is provided at certain advantageous places with 10 glass panels 66, so that various inspections can be made without opening the panels. However, as such refinements are not a part of the present invention, they will not be described in detail. 15

With reference to Figs. 1 and 2, the indicator lamps 51 are shown, which lamps have numbers formed thereon, designating the number of the lever above which it is located. It will also be noted, that the handle grips of alternate levers 20 are pointing downward, and the remaining levers are pointing upward, which facilitates making the various levers accessible to control by an operator. Also associated with each lever are the indicator lights 52 and 53 used for suitable indication purposes, and also a push button 54 which governs the operation of the mechanical stick type contact control 22. 25

In Fig. 3 is shown in detail a mechanical stick type circuit controller 22 associated with the 30 lever L and the push button 54. As heretofore stated, the frame 22 of the mechanical stick type circuit controller is mounted on the bed member 16 and furnishes a guiding support for the rod 55, which transmits the motion of push button 54 to the various contacts of the contactor by compressing coil spring 56, forcing a link 57 against a contact support 58, which is pivoted on pin 59 attached to the fixed contact support 60, which is also mounted upon the main frame 22 40 of the mechanical stick type contactor.

A cam member 61 is mounted upon the lever L, in such a manner, that a plunger 62 is forced upward biasing a coil spring 63. With the plunger 62 forced to an upper extreme position, a projection 62^b on the plunger 62 fits into the circular slot 55^a cut into the rod member 55. Now it will be noted, if the lever L is moved to the left, to an intermediate position, the cam member 61 is also moved to the left and allows the coil spring 50 63 to force the plunger 62 in a downward direction, to unlock 55, and when lever L is moved further, to its other extreme position, if the push button 54 is depressed, the motion will be transmitted through the rod 55 biasing coil spring 56, 55 until slot 55^a is opposite a projection 62^a which is forced into said slot 55^a. Thus, the push button 54 is locked in a depressed position, until the lever L is again moved to the right, to its intermediate position, at which time the cam member 61 will 60 force the plunger 62 in an upward direction releasing the rod 55.

The motion which is transmitted to the movable contact support 58 controls contact fingers 64 to engage with certain fixed contacts 70 and 71 65 for controlling suitable circuits thereby.

Such a mechanical stick type contactor is associated with certain signal levers for controlling a "call-on" signal associated with a particular signal, so that, if the main signal is controlled 70 to a reverse or clear condition in the interlocking tower, but is prevented from assuming that condition because of occupancy of its track section, or the like, then the "call-on" signal may be cleared by depression of a push button, such 75

as push button 54. A "call-on" signal cannot remain cleared unless the signal lever with which it is associated, is maintained in a reverse or cleared position. Thus, the movement of the 5 main signal lever to a stop or normal position automatically releases the rod 55 and allows the spring 56 to control the "call-on" signal to a stop or normal condition.

In Figs. 4 and 5 the lever L is shown as composed of two lever members L^a and L^b. The lever member L^a is a casting having a hollow portion for containing various movable parts and is suitably connected to the lever member L^b which is of solid bar construction. The lever member L^b 15 fits within the guiding slots provided in the bed member 16, thus supporting the lever member L^a which forms the handle grip controlled by the operator.

Within the lever member L^a, a latch member 20 72 is pivotally attached to the lever member L^a by a pin 73, and is controlled to an extreme biased position as shown in Fig. 4 by a coil spring 74 the tension of which is adjustable by a screw 75. This lever latch 72 has a slot 72^a within which a square 25 movable pivot member 80 may slide. Two levers 76 and 77 are pivotally mounted upon support members 78 and 79, which support members are suitably attached to the bed member 16 (see Fig. 1). These levers 76 and 77 are placed on opposite sides of the lever member L^a (see Fig. 5) so that their extreme ends may be pivotally attached to the movable pivot member 80. In order that the square movable pivot member 80 may interconnect the levers 76 and 77 a slot L^c is provided 30 in the casing of lever member L^b, which slot L^c extends in a direction parallel with the direction of the lever L and at each end has portions extending at right angles to the direction of the lever L. With the lever L in the position as 35 shown in Fig. 4, the pivot member 80 is in the left hand vertical portion of the slot L^c due to the bias of coil spring 74, thus preventing the movement of the lever L. The slot 72^a does not coincide with the slot L^c until the latch 72 has been 40 manually compressed, at which time, the movable pivot member 80 disengages the lever L so that it may be moved in a left hand direction. When the lever L has been moved to the reverse position the latch 72 may be released, at which 45 time the pivot member 80 is moved upward into the right hand vertical portion of the slot L^c. It will now be seen that the lever L cannot be moved from either extreme position until the lever latch 72 has been operated so that the slot 50 72^a coincides with the slot L^c, thus causing the movable pivot member 80 to disengage the lever L.

It will now be noted that the pivot member 80 assumes a lower extreme position, with the lever 55 L in a position as shown (see Fig. 4) and assumes a central position when the lever latch 72 is pressed, which position is maintained until the lever L is moved to a left hand position, so that the lever latch 72 may be released at which time the pivot member assumes an upper extreme position. As the levers 76 and 77 are controlled by the pivot member 80, then this motion is transmitted to the tappet bar link 81, so that with the lever L in either extreme position, the tappet bar 60 81 is caused to assume an extreme position, and with the lever latch 72 compressed and the lever L in either extreme position or any intermediate position, the tappet bar 81 is caused to 65 assume a central or intermediate position. Thus, 70 75

the tappet bar 81 being controlled through tappet bar link 81 is operated by the movement of the lever latch 72, or conversely, the mechanical interlocking between the various tappet bars governs the movement of the lever latch 72 which in turn governs the movement of the lever L.

As alternate levers have their handle grips extending upward, the pivot member 80, in such levers, will assume an upper position with the lever L in the normal position and assume a lower position with the lever L in a reverse position. This condition causes alternate tappet bars to assume opposite extreme positions, that is, the tappet bars are operated in an opposite direction upon actuation of their controlling lever latch. 15

The tappet bar link 81 has its upper end forked in such a manner that the tappet bar link passes on each side of the lever member L^b to engage the lever members 76 and 77. The ends of the lever members 76 and 77 engage the tappet bar 20 link 81 within slots formed in the tappet bar link 81 with the vertical motion of the tappet bar link 81 made possible by the rounded end portions of the levers 76 and 77. The tappet bar link 81 is held into position against the bed member 25 16 by projections 78^a and 79^a on the support members 78 and 79 respectively. There are also provided projections 78^b and 79^b upon the support members 78 and 79 to serve as a part of the guides of other tappet bar links (not shown) on 30 each side of the lever L.

Also associated with the operation of the latch 72 is the force drop electric lock controlling contact 82, which is operated by the movement of a bar 83 which is pivoted to the lever member L^a 35 by a pin 88. The bar 83 is moved in an upper direction, as seen in Fig. 4, by the engagement of the lever latch 72 with an adjustable stop 86 with the motion of lever 83 transmitted to the contact 82 through an insulating member 84 40 45 which engages the movable spring contact 82, to force it against the fixed contact member 82^a.

Thus, a compact organization and construction of interrelated devices for interlocking systems has been shown and described as forming the interlocking machine of the present invention, with each device particularly adapted to coact with every other device in a manner to accomplish an efficient control of a distant switch machine, a distant signal or any other traffic controlling 50 device, with each device arranged in a manner to facilitate in its inspection, adjustment and repair.

Having described one specific embodiment of the present invention, it is to be understood that 55 various modifications, adaptations and alterations may be made without departing from the spirit or scope of the present invention as demanded by the following claims.

Having described my invention, I now claim:— 60

1. In an interlocking machine for railroads, a plurality of vertically positioned front frame members, a plurality of vertically positioned back frame members, a plurality of horizontal frame cross members interconnecting said right and 65 left hand vertically positioned frame members, mounting means comprising a plurality of bed members interconnecting said vertically positioned right and left hand frame members and interconnecting said horizontal frame cross 70 members, a plurality of mechanical and electro-mechanical interlocking control devices mounted upon said mounting means, and a pit located between said right and left hand vertically positioned frame members and below the floor level 75

to accomplish accessibility of said plurality of mechanical and electro-mechanical control devices.

2. In an interlocking machine for railroads, a plurality of control levers for controlling the operation of distant railroad traffic regulating devices, a plurality of circuit controllers, a pit creating a depressed floor level between said control levers and said circuit controllers, and means 10 operating said circuit controllers upon operation of said control levers.

3. In an interlocking machine for railroads, a plurality of slidably mounted control levers operating their respective traffic regulating devices, 15 a plurality of slidably operated circuit controllers mounted at right angles to said control levers, and means operatively connecting each circuit controller with its respective control lever including, a pivoted lever, a link pivotally connecting 20 one end of said pivoted lever with said circuit controller, and means slidably connecting the opposite end of said pivoted lever to said control lever including, a cam slot in said control lever.

4. In an interlocking machine for railroads, a plurality of vertically disposed mechanical interlocking plates, a plurality of slidably operated latch locked control levers horizontally disposed, a plurality of reciprocating circuit controllers operated by said control levers respectively, a 25 plurality of vertically disposed circuit controllers, a passage way between said vertically disposed mechanical interlocking plates and said vertically disposed circuit controllers, and beneath said horizontally disposed control levers, 30 and means operatively connecting said latch locked control levers with said vertically disposed circuit controllers respectively.

5. In an interlocking machine for railroads, a plurality of vertically positioned right hand frame members, a plurality of right hand vertical bed members, connecting said vertically positioned right hand frame members, a plurality of slidably operated circuit controllers mounted upon said right hand vertical bed members, a plurality of vertically positioned left hand frame members, a plurality of left hand vertical bed members, a plurality of mechanical interlocking plates mounted upon said left hand vertical bed members, a plurality of horizontal frame cross members connecting said right hand and left hand vertical frame members, a plurality of horizontal bed members connecting said horizontal frame members, a plurality of interlocking control devices mounted upon said horizontal bed members, including, a plurality of control levers mechanically and electrically interlocked, a plurality of electric locks, a plurality of mechanical stick-type push buttons, a plurality of reciprocating circuit controllers, a plurality of indication selectors, a plurality of polarized cross protection relays, a plurality of fuse blocks, a plurality of indication latches, a plurality of indication magnets, a plurality of safety magnets, means operably connecting said control levers 55 with said slidably operated circuit controllers, and means operably controlling movement of said control lever including mechanical interlocking means mounted on said mechanical interlocking plates.

70. 6. In an interlocking machine, a longitudinally slidably operated control lever, a tappet bar operable at an angle thereto, a lever latch, means controlled by said lever latch for directly locking said control lever against movement, and means operably controlling movement of said 75

tappet bar, said last mentioned means governed by said control lever and said lever latch.

7. In an interlocking machine, a longitudinally slidably operated control lever, a tappet bar slidably operable in a direction substantially perpendicular to the direction of movement of said control lever, a lever latch, locking means controlled by said lever latch operably preventing movement of said control lever, means controlled by said lever latch operably controlling movement of said tappet bar and releasing said locking means, and means preventing movement of said lever latch with said control lever in an intermediate position.

8. In an interlocking machine, a plurality of 15 slidably operated control levers, a plurality of vertically positioned interlocking plates, a plurality of tappet bars mounted on said interlocking plates being slidably operable in a vertical direction and being mechanically interlocked, 20 a lever latch associated with each control lever, means operable for preventing movement of each of said control levers with said means operably controlled by the respective said lever latches, and means associated with each control lever 25 operably controlling each tappet bar associated with that lever, in a vertical direction with said means operably controlled by said lever latch and passively controlled by said control lever.

9. In an interlocking machine, a slidably operated control lever, a tappet bar operable in a vertical direction, a lever latch, means controlled by said lever latch locking movement of said control lever, and means operably controlling movement of said tappet bar to one extreme 30 position with said control lever locked in one extreme position and said lever latch released, operably controlling movement of said tappet bar to an intermediate position with said control lever in either extreme position or any intermediate 35 position and said lever latch being actuated, and operably controlling movement of said tappet bar to an opposite extreme position with said control lever in an opposite extreme position and said lever latch released.

10. In an interlocking machine, plurality of slidably operable control levers, a lever latch on each control lever, mechanical interlocking means governing movement of said control levers, means operably controlled by said lever latch for jointly locking said control lever and operating said mechanical interlocking means, whereby said mechanical interlocking can prevent movement of said lever latch which in turn prevents movement of said control lever.

11. In an interlocking machine for railroads, a slidably operated control lever, a lever latch biased to one extreme position and locking said control lever only when in that biased position, a tappet bar, two centrally pivoted levers controlling said tappet bar, means slidably connecting said two centrally pivoted levers to said lever latch, and means allowing said tappet bar to be controlled to an extreme position by said lever latch biased to an extreme position and causing 60 said lever latch to control said tappet bar to an intermediate position with said control lever in an intermediate position.

12. In an interlocking machine, a longitudinally slidably operable control lever, a tappet bar, 70 a lever latch, means controlled by the lever latch for directly locking the control lever against movement, and means operably interconnecting the tappet bar and the lever latch.

13. In an interlocking machine for railroads 75

and the like, a slidable control lever, a circuit controller positioned beyond one end of the lever, a pivoted arm substantially parallelling the control lever, means connecting the arm and circuit controller at one end, and a pin and cam slot connecting the other end of the arm and control lever.

14. In an interlocking machine, in combination, a longitudinally slidable control lever, a tappet bar, a lever latch carried by the control lever, means controlled by the lever latch for controlling movement of the lever, and operable means interconnecting the tappet bar and the latch.

15. 15. In an interlocking machine, in combination, a longitudinally slidable control lever, a tappet bar, a pivoted lever latch carried by the control lever, pin and slot locking means controlled by the lever latch for controlling movement of the lever, and operable means interconnecting the tappet bar and the latch.

16. In an interlocking machine, in combination, a slidable control lever, a tappet bar, a pivoted lever latch carried by the control lever, pin and slot locking means controlled by the lever latch for controlling movement of the lever and operable means including a rod carrying the lock pin interconnecting the tappet bar and the latch.

30 17. A control lever, a hollow handle for operating the lever, a pivoted latch carried by the lever adjacent the handle, biasing means for the latch carried in the hollow handle, a slot in the lever, a lock pin movable in the handle and the slot, and a connection between the pin and the latch.

40 18. A slidable control lever, a hollow handle for operating the lever, a biased pivoted latch carried by the lever adjacent the handle, a slot in the lever, a lock pin in the handle and mov-

able in the slot, and a connection between the pin and the latch.

19. A slidable control lever, a handle for operating the lever, a biased pivoted latch carried by the lever adjacent the handle, a Z-shaped slot in the lever, a lock pin movable in the slot, and a connection between the pin and the latch whereby the pin is biased toward one or the other of the end portions of the Z-shaped slot, the pin and the slot cooperating when the pin is in either of the end portions of the Z-shaped slot, to lock the lever against movement.

20. A slidable control lever, a handle for operating the lever, a biased pivoted latch carried by the lever adjacent the handle, a slot in the lever, a lock pin movable in the slot, and a connection between the pin and the latch, the pin and the slot cooperating to at various positions lock the lever against movement, a tappet bar, and a rod carrying the lock pin and controlled by the position of the tappet bar.

21. A control lever, a handle for operating the lever, a biased pivoted latch carried by the lever adjacent the handle, a slot in the lever, a lock pin movable in the slot, and a connection between the pin and the latch, the pin and the slot cooperating to at various positions lock the lever against movement, a tappet bar, and a rod carrying the lock pin and controlled by the position of the tappet bar.

22. A control lever, a receiving frame in which the lever is movable, a hollow handle for operating the lever, a pivoted latch carried by the lever adjacent the handle, slots in the lever and the latch, a lock pin carried by the frame and movable in the slots and operable at times to lock the lever to the frame, the pin being movable by the latch.
